UNITED STATES PATENT OFFICE.

MARION MATHER, OF OLEAN, NEW YORK.

CARD-EXHIBITOR.

1,354,261.

Specification of Letters Patent. Patented Sept. 28, 1920.

Application filed June 10, 1920. Serial No. 287,927.

To all whom it may concern:

Be it known that I, MARION MATHER, a citizen of the United States, residing at Olean, in the county of Cattaraugus and State of New York, have invented certain new and useful Improvements in Card-Exhibitors, of which the following is a specification.

This invention relates to machines for exhibiting a series of cards or other similar objects one after another; and it consists in the novel construction and combination of the parts hereinafter fully described and claimed.

In the drawings, Figure 1 is a vertical section of a card exhibitor constructed according to this invention. Fig. 2 is a sectional plan view, taken on the line 2—2 in Fig. 1. Fig. 3 is a detail view of a card hook and adjacent parts, drawn to a larger scale. Fig. 4 is a cross-section through a card holder.

A suitable inclosing case 4 is provided, and it has an opening or window 5 at its front side where the cards are exhibited. A shaft 6 passes crosswise through the casing behind the window, and is provided with a pulley or wheel 7 for revolving it intermittently by any approved means.

Triangular frames 8 are secured on this shaft, and have laterally projecting flanges 9. Each flange 9 has a slot or opening 10 in its forward end portion, the said frames being revolved by the shaft in the direction of the curved arrow in Fig. 1. A hook 12 is pivoted to the frame in each of its slots 10 by a pin 14.

Curved supporting bars 15 are secured to the ends 16 of the casing 4, and project laterally under the frames 8. These bars 15 are arranged substantially concentric with the shaft 6. The cards 18 to be exhibited have holders 19 of any approved sort attached to their ends, and these holders have laterally projecting lugs 20. Two of these lugs 20 project at the upper corners of the cards, and rest on the supporting bars 15 when the cards are in their normal positions.

As many cards as the bars 15 will hold can be placed in the machine, and exhibited one after another. Each side of each card is provided with matter to be exhibited, and the fronts and the backs of the cards are exhibited alternately. Curved guide bars 24 project from the ends of the casing, and are arranged over the rear and middle portions

of the curved supporting bars 15. The rear ends of the guide bars 24 project above the ends of the supporting bars 15 so that an elongated entrance opening 25 is formed between them.

Reversing levers 26 are provided, and are pivoted to the ends of the casing by pins 27. The lower end portions of these levers normally hang by gravity in a slightly inclined position, and their upper end portions 28 are arranged at an angle to their lower end portions so that they overlap and close the entrance openings 25.

The pivoted hooks 12 slide down the upper sides of the curved guide bars 24, and engage with the upper lugs of each card as it passes from under the guide bars 24. Springs 30 are provided at this point and are secured to the supporting bars 15, to lift up the cards a little so that the hooks may engage with their upper lugs and lift the cards one by one off the supporting bars 15. The frames 8 are provided with catches 31 for engaging with the lower lugs when the cards are lifted off the bars 15, and are displayed at the window.

The machine is operated intermittently so that the cards are held stationary at the window for a predetermined space of time.

When the cards are carried around to the back part of the casing by the triangular frames, the lugs 20 which were uppermost when the cards were being displayed slide over the upper end portions of the reversing levers, and bear against their lower end portions, so that the reversing levers are tilted a little on their pivots to permit the other lugs on the cards to pass through the entrance opening 25 between the two curved bars. The upper lugs of the cards now become their lower lugs, so that the cards are reversed, and the second time they are exhibited at the window their backs are shown instead of their fronts. The catches 31 assist in guiding the lugs into the entrance opening 25; and the hooks are disengaged from the lugs by contact with the top edges of the guide bars 24.

When the lugs on the cards have passed through the entrance opening 25, the cards descend by gravity clear of the lower end portions of the reversing levers, and are picked up one by one as hereinbefore described at the front part of the machine.

What I claim is:

1. In a card exhibitor, revoluble frames

- provided with pivoted hooks for engaging with the cards, curved supporting bars and guide bars for the cards, cards provided with lugs which pass between the said bars, and pivoted reversing levers normally closing the entrance opening between the said bars and operated by the said lugs and enabling the fronts and backs of the cards to be displayed alternately.
- 10 2. In a card exhibitor, revoluble triangular frames provided with laterally projecting flanges which have slots in their forward end portions, hooks pivoted in the said slots and adapted to engage with the cards, curved supporting bars and guide bars for the cards, cards provided with lugs which pass between the said bars, and pivoted reversing levers normally closing the entrance opening between the said bars and operated by the said lugs and enabling the fronts and backs of the cards to be displayed alternately.
- 15 3. In a card exhibitor, revoluble frames provided with pivoted hooks for engaging with the cards, curved supporting bars and guide bars arranged substantially concentric with the frames, the front end portions of the supporting bars being arranged to project forwardly beyond the front ends of

the guide bars, and the rear ends of the 30 guide bars being arranged to project above the rear ends of the supporting bars and and form entrance openings, cards provided with lugs which pass between the said bars, and pivoted reversing levers normally 35 closing the said openings and operated by the lugs on the cards and enabling the fronts and backs of the cards to be displayed alternately.

4. In a card exhibitor, revoluble frames 40 provided with pivoted hooks and catches for engaging with the cards, curved supporting bars and guide bars for the cards, cards provided with lugs which pass between the said bars, springs for raising the 45 cards as they pass from under the front ends of the guide bars, the said hooks being moved pivotally by the said guide bars into and out of engagement with the lugs on the cards, and pivoted reversing levers operated by the said lugs and normally closing the entrance opening between the said bars, and enabling the fronts and backs of the cards to be displayed alternately.

In testimony whereof I have affixed my 55 signature.

MARION MATHER.
